UNITED STATES PATENT OFFICE.

JACOBUS VAN KATWYK, OF BROOKLYN, NEW YORK.

CYLINDER-SCREW.

1,070,560.

Specification of Letters Patent. Patented Aug. 19, 1913.

Application filed May 25, 1912. Serial No. 699,736.

To all whom it may concern:

Be it known that I, JACOBUS VAN KATWYK, a subject of the Queen of the Netherlands, residing at Brooklyn, in the county 5 of Kings and State of New York, have invented certain new and useful Improvements in Cylinder-Screws, of which the following is a specification, reference being had therein to the accompanying drawing.

- 10 This invention relates to boats, and the principal object of the same is to provide the boat with a novel type of propelling means which comprises cylinder screws which are mounted in the chambers formed in the 15 hull of the vessel, the chambers being provided with sliding doors so that the chambers may be closed thus shutting off the water from the cylinder screws and permitting the doors of the chambers to be opened 20 from the inside of the boat to permit the cylinder screws to be cleaned when necessary.

This invention is illustrated in the accompanying drawing, wherein:—

25 Figure 1 is a side elevation of a ship showing the cylinder screws in position. Fig. 2 is a longitudinal sectional view with the screw housing and doors removed. Fig. 3 is a transverse sectional view through one 30 of the propeller housings. Fig. 4 is a fragmentary longitudinal sectional view through one of the propeller housings with the doors in position.

Referring to the drawings, it will be seen 35 that this invention comprises a number of cylinder screws which are mounted in the hull 30 of the vessel and are positioned in chambers which are located along the keel of the boat. Each of these cylinders has its 40 own engine so that if the engine running one of the cylinder screws gets out of order, the boat will not necessarily be stopped as the engines running the remaining cylinder screws will not be interfered with. It will 45 thus be seen that the cylinder screws may be independently cleaned or repaired without it being necessary to stop the remaining screws and also that repairing may be done without it being necessary to stop the ship or to 50 place the ship in dry-dock.

The bottom of the ship 30 is provided 55 with air-tight bulk-heads 31, which inclose openings formed in the bottom of the ship, each bulk-head being provided with a water-tight closure 32 which may be opened when it is desired to enter the bulk-head. Flanges

33 extend from the sides of the opening formed in the bottom of the ship and form supports for the doors 34 and 35 when the doors are lowered. The propeller housing 60 36 is located within the bulk-head and is supported at each end by the bearings 37 mounted upon the propeller shaft 38. This propeller shaft passes through bearings 39 at the ends of the bulk-head and a driving belt 40 is mounted upon a pulley 41 at the outer end of the shaft. It is of course obvious that, if desired, driving belts may be applied to each end of the propeller shaft.

The doors 34 and 35 are provided with 70 bearings 42 and 43 which are mounted upon the propeller shaft 38 so that the doors will be rotatably mounted. The lower edge of the door 35 is sharpened to form a reduced edge 44 which fits into a pocket 45 formed 75 in the door 34. The upper portion of each of the doors is provided with an inwardly extending flange 46 which engages a flange 47 at the lower edges of the propeller housing 36. Above the flanges 46, the doors are 80 flared and extend to the bulk-head where they are bent to form the flanges 48 which rest upon the flanges 33. It will thus be seen that when the doors are lowered that they are supported by the flanges 46 and 48 85 which rest upon the flanges 47 and 33. In the preferred form rubber packing strips are mounted upon the flanges 33 and 47 so that when the doors are lowered water-tight joints will be formed between the doors and 90 the supporting flanges. These doors are opened and closed by being rotated upon the propeller shaft, the rotation of the doors being accomplished by the following mechanism:—Curved rack-bars 49 extend from 95 each of the doors and are positioned out of alignment so that the racks may pass each other. The free ends of the rack-bars pass through guides 50 and are operated by gear wheels 51 mounted upon the shafts 52. 100 Each of these shafts 52 is mounted in a bearing 53 carried by the propeller housing and extend through a bearing formed in the bulk-head so that an operating wheel 54 may be mounted upon its outer end. An 105 opening is formed in the upper portion of the propeller housing beneath the opening formed in the bulk-head and is closed by water-tight closure 55 which may be opened when it is desired to examine the propeller. 110 When the ship is in motion the shafts 52 are rotated so that the doors 34 and 35 will be

drawn up into the place between the propeller housing and the bulkhead, thus exposing the propeller and permitting it to force the ship forward. When it is desired 5 to examine the propeller, the shafts 52 are rotated so that the doors are lowered to the position shown in Fig. 7; the lower ends of the doors interlocking and the doors being supported upon the rubber packing strips 10 carried by the flanges 33 and 47. After these doors are lowered, it will, of course, be obvious that the propeller housing and the space between the propeller housing and the bulkhead will be filled with water. In 15 order to remove this water a pump which is connected with the pipe 56 is set in operation and the water will be pumped out of the space between the bulkhead and the propeller housing. The closure 32 can now be 20 opened and the closure 55 then opened so that access may be had to the propeller housing. A suction pump is passed into the propeller housing and the water pumped out. The propeller can then be scraped or 25 repaired. After the propeller has been cleaned the closures 32 and 55 are closed and the doors can then be raised and the propeller started.

What is claimed is:—

- 30 1. A ship, propeller housings carried by said ship, propellers mounted in said housings, and sectional doors between said propeller and housing, and adapted to be swung down beneath said propeller.
- 35 2. In a ship, a bulk-head mounted in the hull thereof, a propeller shaft passing through said bulk-head, a propeller housing mounted on said shaft, a propeller carried by said shaft and in said propeller housing, 40 and closures mounted upon said propeller

shaft and adapted to be moved from within the space between said propeller housing and said bulk-head to a position beneath said propeller to close said propeller housing and the space between said propeller housing and said bulk-head. 45

3. A ship having an opening formed in its hull, a bulk-head mounted in the hull of said ship and inclosing the opening formed therein, a propeller shaft passing through 50 said bulk-head, a propeller housing mounted upon said propeller shaft, flanges formed at the lower edges of said bulk-head and propeller housing, and closures positioned between said bulk-head and said propeller 55 housing and adapted to be lowered to rest upon said flanges and having their edges interlocking to close said propeller housing and the space between said propeller housing and said bulk-head. 60

4. A ship having an opening formed in its hull, a bulk-head inclosing the opening formed in said hull, a propeller shaft passing through said bulk-head, a propeller housing mounted upon said shaft, closures 65 mounted upon said shaft and adapted to move between said bulk-head and said propeller housing, curved rack-bars carried by said closures, shafts mounted between said bulk-head and propeller housing, and gear 70 wheels mounted upon said shafts and meshing with said rack-bars to raise and lower said closures.

In testimony whereof I hereunto affix my signature in presence of two witnesses.

JACOBUS VAN KATWYK.
